UNITED STATES PATENT OFFICE.

HENRY H. LAMPERT, OF CHICAGO, ILLINOIS.

POST HEAD.

Application filed January 8, 1926. Serial No. 80,109.

This invention relates to improved means for attaching a cross beam on the end of a post and is particularly adapted for use in concrete form construction for fitting and securing together the structural members of the temporary forms.

Since the concrete forms are temporarily set up for use and then taken down and stored until again required, and used over and over again, many of the details of construction, such as attaching a beam to a post, may be standardized and used with light modifications in the many different structures.

The main objects of the present invention are to provide an improved post head or fitting, whereby two parts of a form disposed transversely to each other may be quickly assembled with a saving in the labor and may be quickly and completely disassembled to save storage space; to provide a fitting of this kind which is readily adjustable; and to provide a fitting of this character which is simple in operation so that it may be applied by even unskilled labor.

An illustrative embodiment of this invention is shown in the accompanying drawings, in which:

30 Figure 1 is an elevation of the improved post head showing it applied to an upright post and a horizontal stringer.

Fig. 2 is an elevation taken from the right of Fig. 1.

35 Fig. 3 is a plan of the fitting in place on the post, a portion of the stringer being shown in dotted outline.

Fig. 4 is an elevation similar to Fig. 1, showing a modified form of post head.

40 In the form shown, the attachment embraces the stringer and is preferably nailed thereto. A socket member or sleeve is provided in the attachment for fitting over the upper end of the post and one or more wedges may be driven through the side of the sleeve for securing the attachment to the post.

In the drawings, a beam or stringer 1 is shown resting on the top of a post 2 and secured thereto by means of an improved fitting comprising a sleeve or collar portion 3 adapted to embrace the end of the post and having upstanding flanges 4 for embracing the stringer 1. The fitting may be secured to the stringer by nails or other suit-

able fastening means 5 and is secured to the post by one or more wedges 6 and 7. The parts are preferably so relatively arranged that the stringer rests directly on the post end. The wedges 6 and 7 are seated in keyways or pockets 8 and 9 respectively formed on adjacent sides of the collar 3, and located in different planes so that the wedges will not interfere with each other. The keyways 8 and 9 extend through the walls of the sleeve 3 so as to permit the wedges to engage the sides of the post. When the wedges are driven, they are jammed between the angularly disposed outer walls 10 of the pockets 8 or 9 and the adjacent edge of the beam and effectually lock the fitting in place.

Inasmuch as the weight of the transverse member may be carried directly by the post 2, the attachment may serve merely as a means for holding the stringer in place. The adjustments may be readily made and the attachment is adaptable to slight variations in size of the timbers used. In disassembling, the wedges are knocked out and the stringer removed from the post. The fitting may be left nailed to the beam or nails withdrawn with very little difficulty and the structure is thereby quickly disassembled.

In the forms shown in Figures 1, 2 and 3, a fitting is shown which is adaptable to timbers of approximately the same thickness. In the form shown in Figure 4, in which the upright flanges 4 are spaced inwardly from the sides of the sleeve, a narrower beam may be used.

Although but one specific embodiment of this invention has been herein shown and described, it will be understood that certain details of the construction shown may be altered or omitted without departing from the spirit of this invention:

I claim:

1. In a device of the class described, the combination with a pair of structural members arranged in abutting relation, of a collar having an opening extending therethrough, one of said members extending through said opening and projecting beyond the ends thereof, the other of said members being supported on one of the projecting extremities of said one member, two sides of said collar being extended beyond said extremity to provide a pair of

spaced flanges embracing said other member, and means for securing said members respectively to said collar and flanges.

2. In concrete form construction, a post and a transverse beam resting on one extremity of the post, a sleeve slidable on the post and having flanges nailed to the beam,

and a pair of transversely disposed wedges in the sleeve for securing the sleeve to the post.

Signed at Chicago this 30 day of Dec. 1925.

HENRY H. LAMPERT.
